UNITED STATES PATENT OFFICE.

EDWARD CHESHIRE, OF PITTSBURGH, PENNSYLVANIA, ASSIGNEE TO MILLER SAW TRIMMER COMPANY OF MICHIGAN, OF PITTSBURGH, PENNSYLVANIA, A CORPORATION OF MICHIGAN.

SHEET-STACKER.

1,194,328

Specification of Letters Patent.

Patented Aug. 8, 1916.

Application filed September 18, 1913. Serial No. 790,529.

To all whom it may concern:

Be it known that I, EDWARD CHESHIRE, a citizen of the United States, residing at Pittsburgh, in the county of Allegheny and 5 State of Pennsylvania, have invented new and useful Improvements in Sheet-Stackers, of which the following is a full, clear, concise, and exact description, reference being had to the accompanying drawing, forming 10 a part of this specification.

My invention pertains to sheet stacking devices.

Where sheets are delivered one by one upon each other so as to form a pile, and 15 especially where such delivery is effected mechanically, it is desirable that means be provided for forming the sheets into a neat pile; and various sheet stacking mechanisms have been devised from time to time with a view 20 to effecting this.

It is an object of the present invention to improve upon devices of this character.

It is a further object of the invention to provide a simple and efficient sheet stacking 25 device which will prevent the sheets from piling up to a greater extent at the lower edges than at the top edges when an inclined table is used.

Other and further objects of the invention 30 will be apparent from the following specification taken in connection with the appended claims.

I have described in the following specification and shown in the accompanying 35 drawings a sheet stacking device of a kind particularly applicable to a paper feeding and handling mechanism of the kind described in my co-pending application, Serial No. 790,525, filed Sept. 18, 1913. It is to be 40 understood, however, that the invention may be embodied in other constructions than that which is described and shown; and that changes may be made in the details of the construction which is described and shown 45 without exceeding the scope of the invention as defined in the appended claims.

In the drawings: Figure 1 is a plan of a 50 paper feeding and handling device of the kind described in my co-pending application above referred to, having applied thereto a sheet stacking device constructed in accordance with my invention; Fig. 2 is a plan of the sheet stacking device with a portion of the cover plate broken away to disclose the 55 connection between the jogger slides; Fig. 3

is a section on the line 3—3 of Fig. 4, looking in the direction of the arrows, showing the majority of the device in rear elevation; Fig. 4 is a section taken on the line 4—4 of Fig. 2, looking in the direction of the arrows; Fig. 5 is a detail section showing the manner of securing the side joggers to the jogger slides, the section being taken on the line 5—5 of Fig. 2, looking in the direction of the arrows; Fig. 6 is a fragmentary detail section taken on the line 6—6 of Fig. 2 looking in the direction of the arrows; Fig. 7 is a sectional view showing the vertical tappers in rear elevation, the section being taken on the line 7—7 of Fig. 2, looking in the direction of the arrows; Fig. 8 is a detail view of one of the tapper arms. Fig. 9 is a detail section on the line 9—9 of Fig. 2, looking in the direction of the arrows; and, Fig. 10 is a perspective view of the tapper actuating 75 slide.

Like reference characters refer to like parts throughout the following specification and the several figures of the accompanying drawings.

Referring now particularly to Fig. 1, 10 indicates the frame of a paper feeding and handling mechanism of the character described in my co-pending application above referred to, which mechanism includes a 25 feed frame 11 for feeding sheets one by one from a pile of stock to the platen 12 of the press. The feed frame 11 receives its movement from a rockably mounted quadrant 13 which is actuated by a cam 14. The mechanism also includes delivery grippers 15 which take the printed sheets from the platen and drop them one by one upon an inclined receiving table 16 formed at the front of the frame 10. The sheets thus 20 dropped upon the receiving table are packed in a neat pile by means of the mechanism now being described.

The receiving table 16 (Figs. 2—6) is formed with a transverse guide-way in 100 which are mounted a pair of jogger slides 17 and 18 respectively. Each of these slides has formed in the upper face thereof a longitudinal under-cut groove which receives the correspondingly shaped foot 19 of a side 105 jogger 20. The side joggers 20 can be adjusted toward and away from each other by moving them lengthwise in the grooves of their respective slides; and they may be locked in their adjusted position by means of 110.

set screws 21 with which they are provided. The jogger slide 17 is provided with a pin 22 which extends downwardly through a hole in the receiving table and engages a push rod 23 which is mounted in suitable bearings carried by the receiving table. The push rod 23 is forced outward, by means of a spring 24, against a cam projection 25 which is formed on the inner face of the quadrant 13, 10 which has been referred to above as actuating the feed frame 11. It will be seen that when the quadrant 13 is rocked about its pivot the cam 25 will impart to the push rod 23 a reciprocating movement, which movement is communicated to the jogger slide 17.

The jogger slides 17 and 18 are connected by means of a pair of pivoted bell crank levers 26, one arm of each of which engages a notch in one of the jogger slides. The 20 other arms of the bell crank levers interlock with each other. It will be seen that the bell crank levers 26 serve to transmit the reciprocating movements of the slide 17 to the slide 18, the slides moving toward and away from each other. The bell crank levers 26 and the jogger slides 17 and 18 are held in place by means of a removable cover plate 27.

The receiving table 16 is formed with a central longitudinal guide-way in which is 30 mounted a slide 28 having a reduced portion 29 for accommodating the cover plate 27. The slide 28 is formed with a finger hole 30 at its rear end for permitting it to be moved easily in the guide-way. A spring 31 is disposed between the slide 28 and the receiving table 16 for frictionally maintaining the slide in any position to which it may be moved. Mounted on the front edge of the slide 28 is a cross bar 32 having secured 40 thereto a pair of uprights 33, which form an end stop against which the sheets of paper fall when they are released from the grippers 15.

A vertical tapping device is associated 45 with the uprights 33. This tapping device includes a pair of scissors arms 34 and 35 one of which is pivoted to each of the uprights 33. The arm 34 is formed with a rearwardly extending tapper projection 36 50 at its free end. The arm 34 is also formed with a curved slot 37 which receives a pin 38 extending rearwardly from the arm 35. Extending upwardly from the rear end of the pin 38, in a line with the arm 36, is an 55 arm 39 having, at its extreme end, a rearwardly extending tapper projection 40. It will be seen that when one or the other of the arms 34 or 35 is rocked about its pivot, it will communicate such movement to the 60 other arm, the tapper projections 36 and 40 rising or falling according to the direction in which the arm is rocked.

The scissors arm 35 is formed with a projection 41 adjacent its pivot, which projection enters between a pair of teeth formed

upon a slide 42 which is mounted upon the cross bar 32 so as to be capable of longitudinal movement with respect thereto. The slide 42 is retained in position by means of a set screw 43 which passes through a slot 70 in the slide 42 and enters the cross bar 32. The outer end of the slide 42 is engaged by an arm 44 which lies upon the receiving table and is connected at its rear end with the jogger slide 18. It will be seen that when the joggers 20 are moved away from each other, by reason of the cam portion 25 actuating the push rod 23, the tapping projections 36 and 40 fall by reason of the weight of the arms 34 and 35 and the associated parts. When, however, the joggers 20 are moved toward each other under the action of the spring 24 the arm 44 pushes the slide 42 in a direction to cause the tapping projections to rise. 80

In the use of the device, the joggers 20 are adjusted by their slides so as to correspond with the width of the sheets and the position in which they are delivered to the receiving table. The slide 28 is likewise adjusted in accordance with the length of the sheets. The side joggers tap the sheets into proper position, one above the other; and the tapping projections 36 and 40 tap down the front edges of any sheets which may become stacked too high against the uprights 33. It will be noticed that, by reason of the fact that they fall by their weight, the tapper arms adjust themselves automatically to the varying height of the pile of sheets as the same are delivered to the receiving table. 95

Having thus described my invention, what I claim as new and desire to secure by Letters Patent is—

1. In a sheet stacker, in combination, an inclined receiving table having a sheet-engaging end stop at the lower part thereof, and a vertical tapping device associated with said end stop. 105

2. In a sheet stacker, the combination with an inclined table having a fixed sheet-engaging end stop at the lower part thereof, of a pair of oppositely disposed side joggers, means for causing said joggers to reciprocate simultaneously in opposite directions; and a vertical tapping device associated with said end stop to operate upon the sheets in engagement therewith. 110

3. In a sheet stacker, the combination with an inclined table, of a pair of oppositely disposed side joggers slidably mounted thereon, means for causing said joggers to reciprocate simultaneously, a vertical tapping device disposed on said table below said joggers, and means associated with said joggers for operating said tapping device. 120

4. In a sheet stacker, the combination with an inclined receiving table and means for delivering sheets thereto, of a fixed sheet engaging end stop on said table at the 125 130

lower part thereof, and a vertical tapping device associated with said end stop to operate upon the sheets in engagement therewith, said tapping device including a tapping member and tending to move downward, and means for intermittently raising and subsequently releasing said member.

5. In a sheet stacker, a support, a pair of pivoted tapping members extending diagonally across each other and having a slot and pin connection to permit simultaneous

movement of said members about their pivots, and means for intermittently moving one of said members to raise its free end and subsequently releasing said members.

15

In witness whereof, I have hereunto subscribed my name in the presence of two witnesses.

EDWARD CHESHIRE.
